UNITED STATES PATENT OFFICE

GEORGE E. PICKUP, OF NEWARK, OHIO, ASSIGNOR TO THE WEHRLE COMPANY, OF NEWARK, OHIO, A CORPORATION OF OHIO

DESIGN FOR A LIQUID-FUEL STOVE

Application filed December 5, 1929. Serial No. 33,668. Term of patent 7 years.

To all whom it may concern:

Be it known that I, GEORGE E. PICKUP, a citizen of the United States, residing at Newark, in the county of Licking and State of Ohio, have invented a new, original, and ornamental Design for Liquid Fuel Stoves, of which the following is a specification, reference being had to the accompanying drawing, forming a part thereof.

The figure is a perspective view of a liquid fuel stove showing my new design.

I claim:

The ornamental design for a liquid fuel stove, substantially as shown.

GEORGE E. PICKUP.
